UNITED STATES PATENT OFFICE.

ANDREW BERG, OF BRIDGEPORT, CONNECTICUT.

WIRE-CHAIN-MAKING MACHINE.

Application filed January 19, 1921. Serial No. 438,284.

To all whom it may concern:

Be it known that I, ANDREW BERG, citizen of the United States, residing at Bridgeport, in the county of Fairfield and State of Connecticut, have invented certain new and useful Improvements in Wire-Chain-Making Machines; and I do hereby declare the following to be a full, clear, and exact description of the invention, such as will enable others skilled in the art to which it appertains to make and use the same.

This invention relates to wire chain making machines, and is an improvement on the manner of forming the links as set forth in my former patent of October 23, 1917, No. 1,244,448.

Referring to the accompanying drawings wherein the figures and letters of reference indicate like parts throughout the several views:

Figure 1 represents a plan view of the machine and broken view of one of the cams and feed wire:

Figure 2 is a view of the machine looking in the direction of arrow *a*, Figure 1:

Figure 3 is a view of the machine looking in the direction of arrow *b*, Figure 1:

Figure 4 is a broken view of the upper surface of the machine bed, detail plan view of the link forming mandrel and its reciprocating carrier, broken view of the carrier actuating lever, and broken view of the link pivotally connected to the wire gripping lever:

Figure 5 is a broken view of the machine bed, enlarged detail view of the link mandrel, its carrier, its actuating lever, wire gripper and its lever, broken view of the gripper operating lever, all in normal link forming position:

Figure 6 is a view of the same operative elements shown in Figure 5 but in a retreated position:

Figure 7 is an enlarged broken view of the several elements connected with the link forming mechanism in readiness to operate on an advanced section of the feed wire:

Figure 8 is an enlarged broken view of the link carrier jaws and its reciprocating arbor:

Figure 9 is an enlarged broken view of the link forming elements showing wire gripper engaged with the wire and the link carrier in link forming position:

Figure 10 is an enlarged broken view of the link forming elements showing the in-

itial link bending tools advanced to give the initial bend to the link about the mandrel, and the link carrying jaws holding a previously formed link against the mandrel:

Figure 11 is an enlarged broken view of the link forming elements showing the initial link bending tools and link carrying jaws in retreated positions, and the link closers in operative position:

Figure 12 is an enlarged broken view of the wire gripper and initial link bending tools in retreated position, and the link carrying jaws advanced and embracing a recently formed link:

Figure 13 is an enlarged detail cross sectional view of the arbor for the link carrying jaws meshing with the segment lever and broken view of the lever for actuating the segment lever:

1 represents the machine bed with the principal portion of its upper surface covered by the plate 2. 3 is the driving shaft journaled in the hangers 4, Figure 2. This shaft carries the driving pulley 5 and the pinion 6 meshing with the large gear 7 on the cam shaft 8, Figure 1, journaled in the boxes 9. On this shaft are mounted the cams 10, 11, 12, 13, 14, and 15. The shaft 16 is journaled in the boxes 17, 18, and it carries the cams 19, 20, and pinion 21, Figure 2, and is rotatably connected to the shaft 8 through the medium of the bevel gears 22, 23.

24, Figure 8, is an arbor having the link carrying jaws 25 pivotally supported on the pins 26, and 27 is a spring actuating these jaws to grip a link. This U-shaped spring is inserted between that portion of the jaws located within the arbor 24 to give to the gripping of the jaws sufficient flexibility to embrace and grip a link when the arbor is advanced, and will readily let go of the link when the arbor retreats. The arbor 24, Figure 13, is oscillated through the medium of its teeth 24^a meshing with the

toothed segment lever 28 journaled on the pin 29 mounted in the housing 30, Figure 3. 31 is a standard having the box 32 in which is journaled the short shaft 33 carrying the gear 34 rotatably connected, Figure 2, with the shaft 16 through the medium of the pinion 21 on said shaft. The oscillation of the arbor 24 and the segment lever 28 is effected by means of the lever 35, Figures 1 and 2, carrying the pin 36 and roll 37, the latter engaging the cam groove 38 formed in the vertical face of the gear 34, while the inner

end of the lever is pivotally supported on the pin 35^a of the segment lever 28.

The arbor 24 is also longitudinally reciprocated by means of the cam 20, lever 39, Figures 1 and 2, pivotally mounted on the bracket 40 projecting from the machine bed. The inner end of the lever 39 is engaged with the flanged collar 41 mounted on the projecting end of the arbor 24. The arbor 10 teeth 24^a—Figure 13—are of sufficient length to insure engagement of the toothed segment 28 therewith during the longitudinal movements of the arbor.

42, Figures 1, 4, 5, and 6, is the link forming mandrel having a vertical adjustment in the vertically operating mandrel carrier or slide 43. This carrier is reciprocally operated by means of the lever 44 whose inner end, Figure 4, is pivotally connected to the 20 slide by the pin 45; Figures 2 and 5, while its outer end carries the roll 46 adapted to operate in the groove 47 of the cam 19, also shown in Figure 1. The lever 44 is pivotally supported on the pin 44^a, shown dotted in Figure 2.

48, Figures 4, 5, and 6, is a lever carrying the wire gripper 49 adapted to hold a section of wire firmly against the mandrel 42 during the link forming operation. The 30 lower end of this lever is pivotally connected to the carrier 43, and its upper end to the link 50, which link is also pivoted to the arm 51, see also Figures 1 and 3, of the rock shaft 52 journaled in the standard 53. 35 This rock shaft is oscillated by means of the arm 54 whose roll 55 operates in the groove 56 of the cam 13. The wire gripper 49 may form an integral part of the lever 48.

40 57, Figure 1, is a slide whose outer end carries the roll 58 engaging the cam 12 to force the slide towards the former 42 while the roll 59 of the slide, operating in the cam groove 60, formed in the vertical face 45 of the gear 7, serves to return the slide. The cam groove 60 is so shaped and timed with respect to the shape and timing of the cam 12 that the roll 58 is always kept in close contact with the cam. A spring could 50 be employed to withdraw the slide 57 to maintain said contact but it would not be as reliable.

61, 62, Figure 1, are the tools adapted to give the initial bend to a link, and are secured to the slide 57 by the screws 63, 64, and are adjusted thereon by the set screws 65, 66. The link bending tool 62 also serves as a wire cutter as will presently be described.

60 67, Figure 1, is a housing carrying the bushing 68 adjustably secured therein by the screw 69. This bushing, see also Figures 7, 9, 10, 11, and 12, serves as a guide for the feed wire 70. The wire is fed through 65 well known feed roll mechanism, not shown.

In line with said bushing is the wire stop 71 adjustably secured to the machine bed by the screws 72, Figure 1. The severance of a link section from the feed wire 70 is effected by the shearing engagement of 70 the outer face of the tool 62 with the inner face of the bushing 68.

73, 74, Figure 1, are the link closers secured to the angularly disposed slides 75, 76, by the screws 77, 78, and are adjusted on 75 said slides by the screws 79, 80. These link closing slides are actuated to and from the mandrel or former 42 through the medium of the slides 81, 82, whose outer ends carry the rolls 83, 84, engaging the cams 11 80 15, to effect an inward movement of the slides, and a return movement by means of the rolls 85, 86, operating respectively in the grooves 87, 88, of the cams 10, 14. The slides 81, 82, are reciprocated in the same 85 manner as heretofore described for slide 57.

The slides 81, 82, are provided with the rack teeth 89, 90, meshing with the pinions 92, 91, journaled on the studs 93, 94. Back 90 teeth 95, 96, are provided on the slides 75, 76, with which the pinions 92, 91, also engage.

The operation of automatically forming a link and interlocking the same into a previously formed link to form a chain, is as follows:—

All of the operative tools for forming a link being in normal open position as shown in Figure 7 with the link carrying jaws 25 holding the previously formed link A, see also Figure 8, the feed wire 70 is automatically advanced against the stop 71, Figure 7. As soon as the end of the wire has thus been advanced against the stop 71, the lever 105 44, Figures 2 and 5, will elevate the carrier 43 from its retreated position shown in Figure 6, to the position shown in Figure 5. During this upward movement of the carrier, the lever 48 will be brought from the 110 inclined position shown in Figure 6 to the vertical position shown in Figure 5, so as to bring the gripper 49 in forcible engagement with the wire and hold the same against the mandrel 42, as shown in Figure 115 9. As before mentioned, this positioning of the gripper 43 is effected through the medium of the cam groove 56, roll 55, rock shaft 52, and rock shaft arms 51, 54, as shown in Figure 1. In the meantime, the 120 arbor 24 will have been advanced to place the previously formed link A, carried by the jaws 25, against the face of the mandrel 42 opposite the wire gripper 43 as shown in Figure 9.

When the gripper 49 and jaws 25 are in the position shown in Figure 9, the initial bending tools 61, 62, Figure 10, are advanced to sever the advanced portion 70^a, Figure 9, into a link section and U-shape 130

it as shown in Figure 10 and will then retreat. While the jaws 25 are still in the position as shown in Figure 10, the link closers 73, 74, are advanced to engage the 5 projecting ends *c*, *d*, of the partially formed link and close them within the previously formed link A, Figure 11. The link closers 73, 74, will remain in this position until the 10 spring actuated jaws 25 have, in their retreat, released themselves from the previously formed link A, when the link closers 73, 74, will retreat into their normal open position, and permit the link A to drop.

In the meantime, the retreating arbor 24 15 will partially rotate to bring the jaws 25 into the position shown in Figure 11, and it will then advance to bring the jaws into engagement with the newly formed link B, Figure 12, whereupon the carrier 43 with the mandrel 42 and gripping lever 48, will 20 retreat and thus release the link B which will be retained by the jaws 25 while the arbor 24 is retreated and partially rotated to bring the jaws into their first position as 25 shown in Figure 7, in readiness for a repetition of the above described link forming process.

The link closers 73, 74, are preferably set at angle so that in their inward travel they 30 will not drag along the closing ends of a link. In other words, their angular path of travel is such that they do not shift their point of contact with the open ends *c*, *d*, during the operation of closing the same. 35 and thereby avoid indenting or otherwise defacing the link.

Having thus described my invention what I claim as new and novel is:—

1. In a wire chain making machine of the 40 character described comprising a bed, a reciprocating mandrel carrier, a link forming mandrel mounted therein, a wire gripping lever pivoted to the carrier, operative means connected with the lever and carrier whereby the lever is moved away from the mandrel when the carrier is retreating, and brought into close relation with the mandrel to hold a section of wire thereagainst during the link forming operation.

50 2. A wire chain making machine of the character described, comprising a reciprocating carrier, a link forming mandrel mounted therein, a wire gripping lever pivoted to the carrier, means whereby said lever is actuated toward the mandrel when the same is advanced, and from said mandrel when it is retreated, initial wire bending tools, a reciprocating support upon which said tools are mounted, and means 55 whereby said support is actuated to and from the mandrel.

60 3. A wire chain making machine of the character described, comprising a mandrel

about which links are formed, a reciprocating carrier for the mandrel, a wire gripper pivoted to the carrier and means for automatically actuating the same toward the mandrel when the same is advanced and from the mandrel when said mandrel is retreated, initial bending tools adapted to 65 sever a section of wire and partially form it into a link about the advanced mandrel, an arbor, jaws carried thereby, means for reciprocating said arbor to and from the mandrel, and means for oscillating the arbor 70 when withdrawn from the mandrel, said jaws adapted to hold a previously formed link against the mandrel, angularly arranged link closers, reciprocating means therefor, said link closers adapted to engage 75 the free ends of the partially formed link and close said ends to form a link within the previously formed link held by the jaws.

4. A wire chain making machine of the character described comprising an automatically operated reciprocating carrier, a mandrel, about which links are adapted to be formed, mounted in the carrier, a wire gripper pivoted to the carrier, and independent means for automatically actuating 80 said wire gripper to and from the mandrel.

5. A wire chain making machine of the character described, comprising link bending tools, a carrier, a link forming mandrel carried thereby, a wire gripper pivoted to 95 the carrier, means for advancing and retreating the carrier to and from the link bending tools, and means for actuating the wire gripper toward the mandrel when the carrier is in its advanced position, and away 100 from the mandrel when the carrier is in its retreated position.

6. A wire chain making machine, comprising a reciprocating carrier, a mandrel mounted therein, a wire gripper pivoted to 105 the carrier, initial link bending tools, an arbor, link holding jaws mounted therein, angularly disposed link closers, means for advancing the gripper to hold a section of the wire against one side of the mandrel, 110 means for advancing the arbor with a previously formed link within the jaws and placing said link against the opposite side of the mandrel, means for advancing the bending tools to sever a section of wire and 115 U-shape it about the mandrel, means for advancing the link closers to close a link within the previously formed link, said arbor retreated after the formation of a link, means for partially rotating the arbor, said arbor 120 again advanced to embrace the newly formed link and again retreat and rotate into its normal position preparatory to the formation of additional links.

In testimony whereof I affix my signature. 125
ANDREW BERG.
